JACQUARD KNITTING MACHINE

Bruno Deri, Brooklyn, and Sebastian Gangi,
New York, N. Y.

Application March 31, 1939, Serial No. 265,162

54 Claims. (Cl. 66—85)

This invention relates to knitting machines and has particular reference to jacquard knitting machines and to methods of knitting.

One object of the invention is to provide an improved machine and method for knitting a fabric with certain weft yarns being continuous and other weft yarns being discontinuous or limited to certain areas of the fabric.

Another object of the invention is the provision of an improved machine of the character described for knitting a fabric having a design consisting of an arrangement of open and filled-in spaces, the weft being confined along the warp yarns to produce the open spaces, and extending across from one warp yarn to another to produce the filled-in spaces, and a ground weft extending at predetermined intervals across the fabric to define the spaces and to interconnect the warp yarns at the open spaces.

Another object of the invention is the provision of improved means to cause relative reciprocatory motion between the needles and certain of their individual yarn carriers for producing open work or filled-in spaces by selectively varying the relative reciprocation with respect to one needle or a plurality of needles.

Another object of the invention is to provide improved means whereby weft yarns are laid into the hooks of needles to thus produce knitted strands of uniform width, in contradistinction to the usual knot-like appearance.

Another object of the invention is to provide an improved jacquard control, such that the jacquard cards are subjected to a minimum pressure by the jacquard pins.

Another object of the invention is the provision of an improved jacquard device having means for releasably selectively holding jacquard knitting control elements in a required position to avoid repeated actuation of parts by the jacquard during a period that the pattern remains unchanged.

Another object of the invention is to provide a machine of the character described having improved means for knitting into the fabric a ground weft that stretches for the entire width of the fabric, in course of knitting open and filled-in spaces, desirably with the weft yarns laid into the needle hooks, all in suitably timed arrangement and in cooperation with each other.

Another object of the invention is to provide a machine as set forth having improved drive means for effecting the several purposes of the machine.

Another object of the invention is to provide

an improved jacquard system, comprising jacquard strips or sections, and feed means for moving the strips to operative and inoperative positions, in a continuous recurrent cycle.

5 A further object of the invention is the provision of an improved method of knitting a fabric with filled-in and open spaces bridged by a knotted or Chainette weft, whose knots engage with the stitching to maintain the warp yarns accurately spaced with respect to each other.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated in the annexed drawings, wherein like parts are designated by the same reference characters throughout the several views.

In the drawings:

Figure 1 is a view in elevation of a machine embodying the invention, looking at the left hand end thereof.

Fig. 2 is a view in elevation of a machine embodying the invention looking at the right hand end thereof.

Fig. 3 is a view in front elevation of the machine.

Fig. 4 is a horizontal sectional view taken on the line 4—4 of Fig. 1.

Figs. 5 and 6 are sectional views taken on lines 5—5, and 6—6, respectively, of Fig. 4.

35 Fig. 7 is an enlarged vertical sectional view taken on the broken line 7—7 of Fig. 4, showing part of the yarn feed mechanism for pattern effects, and part of the jacquard system, with the latter further shown in elevation in Fig. 12.

Fig. 8 is a fragmentary enlarged top plan view taken on line 8—8 of Fig. 7, and showing further details of the yarn feed mechanism.

Fig. 9 is a fragmentary plan view of a part of the mechanism of the jacquard system, taken on the line 9—9 of Fig. 2.

Fig. 10 is a sectional view taken on the line 10—10 of Fig. 9.

Fig. 11 is a top plan view of a section of the machine showing the mechanism of Fig. 12.

Fig. 12 is a fragmentary view in elevation taken on the line 12—12 of Fig. 11, and showing the continuous recurrent cycle feeding means of the jacquard system.

Fig. 13 is an enlarged fragmentary plan view 55 of a jacquard pattern strip.

Fig. 15 is a sectional view taken on the line 15—15 of Fig. 13.

Fig. 16 is an enlarged fragmentary sectional view showing means for locking the jacquard pattern strips in operative position on the jacquard bar, and a cam for releasing the locking means.

Fig. 17 is a fragmentary view showing a catch operated by a jacquard strip, shown in dot dash lines, to engage and retain said strip in the full line position thereof, to prevent reverse movement of the said strip from a preliminary station from which it is fed to the jacquard bar.

Fig. 18 is a view in side elevation showing a means for controlling the tension of a cable or ground weft yarn.

Fig. 19A is a diagrammatic view showing the weft laid into the needle hook together with the warp.

Fig. 19B is a view showing the casting off to form the stitch.

Fig. 20 is a diagrammatic view illustrating the reciprocatory path of movement of the weft carrier in laying the yarn into the needle upon each right and left movement of the carrier.

Fig. 21 is a diagrammatic view showing the underlaid weft caught by the warp in knitting filled in spaces of a fabric.

Figs. 22A, 22B and 22C illustrate the movement of the weft carrier in laying yarn under a pair of needles for the knitting of a filled in pattern section.

Fig. 23 is a photographic view of a fabric showing a typical pattern, to illustrate the ability of the machine to knit an infinite variety of patterns without any repeat.

In Figs. 24A to 24D is diagrammatically shown successive positions of the ground weft holding means.

The advantages of the invention as here outlined are best realized when all of its features and instrumentalities are combined in one and the same structure, but, useful devices may be produced embodying less than the whole.

It will be obvious to those skilled in the art to which the invention appertains, that the same may be incorporated in several different constructions. The accompanying drawings, therefore, are submitted merely as showing the preferred exemplification of the invention.

Generally described, this invention provides a machine capable of knitting an infinite variety of patterns, without necessitating any repeat; in other words, if the jacquard provides for infinite variations in design, the machine can proceed to knit the same without any interruption and without requiring any change or adjustment. In principle, certain elements that are used in the knitting operation, such as yarn carriers, are individually movable to one or another of a plurality of groups of the yarn carriers, each of which groups is actuated as a unit for an operation different from that of the other group or groups. The jacquard controls each of these yarn carriers so that each yarn carrier may independently join one or another of the groups for each stitch or series of stitches of the machine. Another principle resides in the provision of means such that, in making a number of stitches according to one pattern, the jacquard and the means responsive thereto are stationary or locked in part to avoid needless motion and wear of the parts. Another principle of the machine is the provision of perforated jacquard

pattern strips, the perforations whereof may be selectively temporarily closed for different pattern effects, so that these strips can be used again and again by varying the operative perforations thereof; and another, or supplemental principle, is to provide a feeding means moving the said strips in an endless path to and from operative pattern controlling position in the machine. The jacquard system is applicable to different kinds of knitting machines. The principle of infinite selective grouping of yarn carriers for group operation is adapted to produce the fabric shown in Fig. 23, with its infinite pattern of open and filled in spaces, and with the yarn carrier motion for filled in spaces illustrated in Figs. 22A—22C.

Referring in detail to the drawings, 25 denotes a knitting machine embodying the invention. While this machine is of the type known as a jacquard knitting machine, certain features of the invention, such as the jacquard system, and others, are applicable to other types of machines, as will be readily apparent to those skilled in the art. For example, the jacquard system may be regarded as a variable selector device.

The machine 25 may have any suitable frame which may comprise end frame members 26, 27 which may be interconnected by cross frame members such as members 28 and 29 at the top and bottom respectively of the machine; and by suitable tie rods as may be required.

Mounted on a bracket carried by the frame member 27 is a motor 30 connected by a belt 31 with a pulley 32, see Fig. 3. Rotated by the pulley 32 is a shaft 33 carrying a bevel gear 34 which rotates a bevel gear 35 of a main drive shaft 36 as shown in Fig. 4. Carried by the shaft 36 are a pair of like spaced cams 37, and a pair of like spaced cams 38. Actuated by the cams 37 in the forward direction are their respective roller carrying follower arms 39; actuated by the cams 38 in the rearward direction are their respective roller carrying follower arms 40. Connected to the arms 39, 40 so as to be thus positively reciprocated in the forward and rearward directions is a needle actuator means 41.

Referring now to Figs. 4 and 7, 42 denotes a stationary slotted needle bed connected to the end frame members 26, 27 and reciprocably carrying the conventional hook and latch needles 43. The latter may have the usual abutments 44 bearing against a bar 45 connected by a plate 46 to the means 41, against which the rear ends of the needles bear. To facilitate replacement of needles, the means 41 may be hollow and open at the front to afford space for rearward removal of the needles, the opening referred to being closed as by a removable plate or angle bar 47, whose upright flange is slidably received in grooves of end lugs 48 of the means 41. Thus the rear ends of the needles bear against the upright flange of the angle bar 47. The means 41 may be slidable along supporting guides 48 fixed on the end frame members 26, 27. Thus it is clear that the cams 37, 38 of the main shaft 36 control the reciprocation of the needles 43.

The weft yarn 49 for the needles is taken from a series of spools 50 mounted on any suitable frame 51 fixed above or on the frame of the machine, the yarns passing downward through a series of spaced openings of any suitable guide means 52. As shown in Fig. 7, the weft yarns then pass a guide bar 53 to a series of weft guides or carriers 54, one of which is provided for each needle. Each weft carrier is capable of movement past a single needle or past a plurality of

needles for the knitting of open work or filled in spaces respectively. The mechanism by which these movements are accomplished will now be described.

Means for selective grouping of weft carriers

As shown particularly in Figs. 7 and 8, each weft carrier 54 of each needle is mounted on an individual rod 55 fixed on its individual horizontal rod 56. Each rod 56 is slidably mounted in holes of the frame bars 57a for longitudinal reciprocatory motion. Each rod 56 is actuated forward by an expansion coil spring 58 which extends around alternate rods 56, or by an expansion coil spring 59 which extends around intermediate rods 56. The purpose of this alternate arrangement is merely to conserve space and permit the rods 56 to lie very close together. Of course each spring 58, 59 bears against an abutment or collar on the rod 56 and against an adjacent frame bar 57a.

Connected to each rod 56 is a link 60 which extends to a jacquard mechanism hereinafter described. The jacquard mechanism pulls any selected rods 56 rearward and releases other rods so that the springs 58, 59 thereof move the same forward. The jacquard may be assumed to be capable of an infinite variety of pattern, and may in the above manner change the position of the weft carriers 54 at each stitching operation of the machine.

Mounted on the frame bars 57a are fixed depending brackets 61, for mounting a plurality of grouping members 62, 63. The latter may be exactly alike, each being a comb-like bar, the spaces between the teeth of the bars being adapted to register with each other. The weft carrier rods 55 pass between the teeth of one or another of the bars 62, 63, and are movable from such engagement by one comb bar to a like engagement by the other comb bar, in response to jacquard operation as aforesaid.

These comb bars 62, 63 are each capable of longitudinal reciprocation, as hereinafter described, the movement of the rear comb bar 63 being greater than that of the front comb bar. The purpose of this is that those weft carrier rods 55 which are engaged by the front comb bar 62 shall move the weft past only a single needle, whereas those rods 55 which are engaged by the rear comb bar 63 shall cause movement of the weft past two or more needles for the filled in knitting. Nevertheless at a certain point in the operation, the slots or spaces in the comb bars are in register with each other so that the rods 55 can move from one to the other as aforesaid. The frame bars 57a are interconnected by end plates 64 to form a unitary frame 57, which is vertically reciprocable by mechanism hereinafter described, simultaneously with the horizontal reciprocation of the comb bars 62, 63, so that the weft carriers 54 may follow a curvilinear or other path relative to the needles for suitably feeding the weft yarn thereto.

It will be understood that the movement of the rods 55 by the comb bars is oscillatory, with the rods 56 being rotatable, but due to the length of the rods 55, their slight movement may be regarded as almost translatory.

In view of the importance of the principle of the comb bars, it is desirable to point out that other specific devices might be used, for actuating each variable group of weft carriers as a unit, by mechanical or other force. If mechanical means are used, it is sufficient that there be

extensions, projections, irregularities or recesses as between the weft carrier means and the horizontal reciprocatory means for suitable interengagement by relative movement between the parts.

Mechanism for actuating the selective grouping means

As hereinbefore pointed out, the jacquard may be regarded as a part of the grouping means, but the mechanism which will now be described is that which controls the comb bars.

Mounted on the main shaft 36 are a plurality of like cams 65, see Figs. 4 and 7, each actuating a follower arm 66 fixed to a rock shaft 67. Referring now to Figs. 1 and 2, the rock shaft 67 may carry oscillatory arms 68, each of which has lost motion pivotal engagement at 69 with the end plates 64 to thus cause vertical reciprocation of the frame 57 which carries the weft feeders 54. To provide for vertical movement of the frame 57, guide means may be provided, such as pins 70 on the frame members 26, 27 which pins serve as guides in slots of the end plates 64.

To cause simultaneous longitudinal reciprocation of the comb bars 62, 63, a drive is provided from the main shaft 36. Referring to Figs. 1 and 4, this drive includes a bevel gear 71 on an end of the main shaft, which drives a bevel gear 72 to rotate a countershaft 73 suitably mounted on the frame member 26 and rotating at the speed of the main shaft 36. On this shaft 73 is a gear 74 which drives a gear 75 to rotate a countershaft 76 suitably mounted on the frame member 26 and rotating at one-half the speed of the main shaft 36. A like arrangement is provided at the right end of the machine as shown in Fig. 2, a gear 74 being mounted on the shaft 33 for rotating the countershaft 76. The shafts 76 each carry a pair of rotary cams 78, 79 which have individual anti-friction engagement with individual follower bars 80, 81, see Fig. 8, which respectively engage the adjacent ends of the comb bars 62, 63. These follower bars are suitably slidably mounted in the end plates 64 or on the frame members 26, 27. Of course the comb bars 62, 63 could directly engage the cams 78, 79, the reason for having the follower bars being to permit clearance adjustment between the cams and the comb bars. The cams 78, 79 at the opposite ends of the comb bars operate conjointly for positively moving the comb bars to the right and to the left. Since the vertical reciprocation of the frame 57 is quite small, the cams 78, 79 will always remain in operative position relative to the comb bars, and the follower bars may have vertical wiping or roller engagement with the ends of the comb bars, as at 82. Since the rear comb bar 63 has a greater travel than the front comb bar 62, the cam 79 has a correspondingly greater pitch or cam incline than the cam 78.

By the conjoint vertical and horizontal reciprocation, the weft carriers 54 may each follow a different curvilinear path as indicated in connection with Fig. 19A for the laying of weft over the needles and in connection with Figs. 22A-22C for laying weft under the needles.

Laying the weft yarn in the needle hooks

When the weft yarns are each fed past a single needle, they are preferably laid into the needle hooks 83 as shown in Figs. 19A, 19B, the purpose being to knit a strand 84 of uniform width instead of one having the appearance of a succession of knots, see Fig. 23. The weft carriers 54 are suit-

ably actuated for this purpose, and lay in the weft first from left to right of a needle, and then from right to left, and so on. Each such laying in operation is effected during a retraction movement of the needle, and at the instant of the laying in, the retraction of the needle is somewhat retarded so as to assure that the weft yarn will be caught in the needle hook. Hence the cams 38 for causing retraction of the needle each have a portion 85 at which such retarded retraction occurs.

After the weft has been laid into the needle hook 83, together with the warp, the continued retraction of the needle causes the needle encircling loop of the strand 84 to slide over and close the tongue 86, with said loop casting off to form a stitch as shown in Fig. 19B. A usual wire 86a holds the tongue open against accidental closing. The added body or thickness distributes itself to form a strand 84 of uniform ribbon-like width. By providing on cam 38 a very small recess at 85a, too small to be shown, the needles are subjected to a kick to jerk the stitches tightly locked. The knitted fabric passes down through a slot 84a in the needle bed, see Fig. 7.

The warp feed control mechanism

Mounted at the base of the machine are a plurality of spools 81, from which warp yarns 88 for the individual needles are fed past a lower guide 89, see Fig. 1, and an upper guide 90, thence to the eyes of the individual fingers 91 for the different needles, see Fig. 7. The upper guide may comprise guide rods 90a, 90b. The fingers 91 are mounted on a rock shaft 92 suitably journaled in the end frame members of the machine.

In Fig. 1 is shown an arm 93 connected to the shaft 92 and having lost motion pivotal engagement at 94 with the lower end of an arm 95 which is fixedly pivotally mounted at its upper end on the frame member 26 of the machine. Coaxially mounted on the shaft 73 is a cylindrical cam 96 which engages a follower portion 97 on the arm 95, so as to cause oscillation of the shaft 92 in course of rotation of the shaft 73. Since the rock shaft 92 is longitudinally reciprocable to a slight degree, some lost motion longitudinally of the shaft may be provided at the pin and slot connection at 94 as clearly shown in Fig. 3.

To provide for longitudinal reciprocation of the rock shaft 92, simultaneously with its rocking motion, an expansion coil spring 92a may bear between the frame member 26 and an abutment or collar on said shaft, as shown in Fig. 3. At the other end of the shaft 92 is a rotary cam 98 fixed on the drive shaft 33 as shown in Fig. 2.

Thus a generally circular movement is imparted to the fingers 91 so as to move the eyes thereof over the needles from left to right over the needles and from right to left under the needles as indicated in Fig. 20 so that the warp is always laid into the needle hooks in a direction from left to right.

Laying the weft yarns under the needles for filled-in knitting

As hereinbefore stated, in knitting filled-in spaces as at 99 of the fabric 100, shown in Fig. 23, the weft yarn is fed under a pair of needles by the weft carrier 54. This is necessary, because the weft yarn would be stripped off and torn if a single yarn were laid into the hooks of more than one needle.

The motion of the weft carriers 54 is clearly shown in Figs. 22A-22C. In Fig. 22A the weft car-

rier is shown descending at the left of a pair of needles 43. In Fig. 22B the weft carrier is shown fully descended. A stitch is being formed at this time as in Fig. 21, hereinafter described, and the carrier rises again before starting movement toward the right above the needles. In Fig. 22C the weft carrier is shown after having completed the rightward movement and a downward movement to place the weft yarn under the pair of needles which are now in fully retracted position. Then the needles are projected. Now a stitch is formed at the right of the needles as in Fig. 21, and the weft carrier return returns leftward over the needles as indicated by the arrow in Fig. 22C, to the position shown in Fig. 22A. The movement is repeated at every stitch in knitting a filled-in section of fabric. The operations at both sides of the pair of needles are identical. Shifting of the weft carriers between the bars 62, 63 necessarily occurs before the weft carriers are returned to positions above the needles.

Considering that there is a weft carrier 54 for every needle, it is interesting to note that a weft carrier which moves past two needles will not interfere with a weft carrier which moves past one needle, because the latter and its carrier rod 55 is forward of the former, and hence there is ample clearance for both motions.

Considering now Fig. 21, it is seen that when the weft 49 is laid below a needle, the finger 91 draws the warp 88 below the weft at 101, and then lays the warp over the needle in a generally diagonal direction, during retraction of the needle. Hence when a stitch is formed in casting off, the weft is naturally caught in that stitch.

Means for feeding the ground weft

Due to the open work knitting, it is desirable to afford a reinforcement to avoid tearing of the fabric. For this purpose, we employ a cable or ground weft 102, for instance, one which is shown in the fabric 100, and is known in the trade as Chainette. The same may have a thin strong strand around which is loosely twisted a heavy strand of relatively hard texture, known in the trade as "frill."

The ground weft 102 may be engaged by the warp yarn and engaged in the resulting stitches in the same manner as the weft yarn is engaged as shown in Fig. 21. The irregularity or twist of the ground weft 102 serves the purpose of preventing the stitches from sliding along the ground weft, because the twist formation affords a good frictional or interlock engagement with the stitches. The ground weft may extend in continuous straight lines along the fabric.

The ground weft is taken from a spool 103 mounted at the top of the machine and guided by a tension control device 104. The same may include a frictional brake 105 actuated by a strip spring 106 into engagement with a shaft portion 107 of the spool. A spring wire 108 is formed with spaced loops 109, 110 through which the ground weft is threaded. A flexible element or cord 111 is connected to the loop 109 and to the free end of the spring 106. If there is considerable slack in the ground weft 102, the spring 108 takes up the same, and the cord 111 becomes slack, so as to prevent any releasing pull thereof on the brake spring 106. Vice versa, if a sudden pull occurs on the ground weft the spring 108 readily yields, especially the part thereof between the eyes 109, 110, and the pull is imparted to the cord 111 thus diminishing the brake action.

The device 104 is very important because the

ground weft is laid down and at considerable tension as will now be described.

From the tension control device 104, a single strand of the ground weft is fed downward past a guide 112 to a feeder tube 113. The element 112 may be a rotary shaft, as hereinafter described, its bearing carrying a bracket 115 at whose lower end is journaled a pulley 120 hereinafter referred to. The element 113 is mounted on a carriage 114 having a bracket arm 116 for this purpose, as shown in Figs. 3, 7 and 8. At each of its upper and lower edges, the carriage 114 is provided with rollers 117 which are engaged in grooves of the track members 118 that extend longitudinally of the machine. For reciprocating the carriage at great speed from end to end of the needle bed, an endless cable 119 may be provided to which the carriage may be suitably affixed.

In principle, the carriage 114 may travel once across the machine for each knitting operation, or after a plurality of knitting operations. According to the particular fabric 100, the machine has been designed so that the carriage 114 makes one course or run of its reciprocation for every six stitches formed by the machine. Accordingly the carriage 114 has a continuous reciprocating motion.

To actuate the cable 119 intermittently back and forth, a pair of pulleys 120, 121 are mounted at opposite ends of the machine, between which lies the drive course for the carriage 114. The cable extends around these pulleys and around a horizontal pulley 122 at the left top of Fig. 3, hence around a pulley 123 shown in Fig. 1, and finally around a large pulley 124 shown in Figs. 1 and 3, and back to the pulley 120.

To drive the pulley 124, reference may be had to the mechanism of Fig. 4 wherein a bevel gear 125 on the main shaft 36 rotates a bevel gear 126 on a cross shaft 127 mounted on the frame of the machine. Carried by the shaft 127 is a bevel gear 128 which drives a bevel gear 129 fixed on the countershaft 130 that is suitably journaled on the frame of the machine. Carried by the shaft 130 is a sprocket wheel 131, connected by a chain 132 with a sprocket wheel 133, also shown in Fig. 1. The sprocket wheel may be mounted on a stub shaft 134 that is journaled on the frame members 26 of the machine. Fixed to said shaft is a disc 135 to which is eccentrically connected at 136 an arm 137 carrying a rack 138 which engages a pinion 139 fixed on a stub shaft 140 on which the pulley 124 is mounted. The said shaft 140 may be suitably journaled on the frame member 26 and may carry a tubular guide or shoe 141 oscillatable about the shaft 140 and serving to maintain the rack 138 in engagement with the pinion 139, as also shown in Fig. 3.

It will be understood that the shaft 130 makes one rotation while the shaft 36 makes six rotations, and that the sprocket wheel 133 makes one-half of a rotation during that time. Hence the rack bar 138 is continuously advanced in one direction while each needle is making six stitches, causing the wheel 124 to actuate the cable 119 to move the carriage 114 across the machine in one direction; during the next six stitches, the same operation occurs in an opposite direction. Thus the ground weft 102 is laid down at reasonable speed in one continuous run of the carriage 114 for every six stitches in accordance with the particular design of the fabric 100. This speed is

much less than if the carriage 114 made a traverse during only one course.

It is necessary that the carriage 114 shall be elevated when the ground weft is laid down, the needles being then retracted, to permit the ground weft to lie close under the needles. Hence the upper and lower rails 118 of the carriage are interconnected at their ends to form a frame which is guided on vertical tracks 142 on the frame members 26, 27, see Figs. 3, 7 and 8. This frame 118 is mounted at each end of the machine on an arm 143 pivotally suspended from a lever 144 as shown in Figs. 1 and 2. Each lever 144 is pivotally mounted at one end at 145 on the machine frame, and has follower engagement at its other end with a cam 146 on which it rests to support the rail frame 118. The cams 146 are fixed on a shaft 112 journaled in the frame members 26, 27.

Since the shaft 112 must be rotated once for every six courses or stitches of the machine, and is idle in the interim, a drive is provided which is suitably timed for this purpose. Hence, referring to Figs. 1 and 4, a segmental gear 148 is mounted on the countershaft 130, arranged to drive a pinion 149 fixed on a shaft 150 that is mounted on the frame member 26. Mounted at the outer end of the shaft 150 is a sprocket wheel 151 connected by a chain 152 with a sprocket wheel 153. The latter is fixed at one end of a shaft 154 which is journaled in the frame members 26, 27, see Figs. 1 and 3. At the other end of said shaft 154 is a sprocket wheel 155, see Figs. 2 and 3, connected by a chain 156 with a sprocket wheel 157 on the shaft 112. A tension adjusting idler pulley 158 for said chain may be mounted on the frame member 27.

It will now be apparent that the shaft 112 is caused to have one rapid rotation after every six courses or stitches performed by the machine, to cause the carriage 114 to be lowered for laying the ground weft closely under the needles while the same are in retracted position, the carriage being then immediately elevated for its next traverse.

Ground weft holding means

It is important that the ground or cable weft shall be caught by an element at the end from which the carriage 114 begins to move and shall be held taut while being engaged by the warp during the stitching, so that the ground weft shall appear smooth and even in the fabric 100. It is also desirable that a slack shall not result in the ground weft where the latter is released from said element.

Referring to Figs. 3 and 7, there is shown a shaft 159 journaled in the frame members 26, 27, or in brackets fixed thereon. Slidably mounted on this shaft are a plurality of fingers 160 normally disposed at opposite ends of the needle bed, and movable toward or away from each other along the shaft according as needles may be removed or inserted to knit a narrow or wide piece of fabric 100. In order to prevent relative rotation between the fingers 160 and the shaft 159, the fingers are desirably releasably clamped thereon as shown.

The shaft 159 has a rocking motion to oscillate the fingers 160 toward and away from the front face or edge of the needle bed 42. When the fingers 160 are thus moved toward the needle bed, the finger 160 which is at that end of the needle bed from which the carriage 114 starts, catches the ground weft 102 and holds it as a guide, while the carriage travels to lay down the ground weft.

Just before the ground weft is caught in the stitches, the fingers 160 are moved away from the needle bed to permit the ground weft to slip off from the finger 160. The operation of both fingers 160 is alike. The action will be further described hereinafter, particularly in connection with Figs. 24A to 24D.

Before describing the actuating means for the rock shaft 159, it will be well to refer to the ground weft holding fingers 161, 162, see Figs. 3 and 7. A pair of the fingers 161 are mounted on a rock shaft 163, and a pair of the fingers 162 are mounted on a rock shaft 164. Both of these shafts are mounted on the frame members 26, 27. A pair of fingers 162 is normally disposed at opposite ends of the needle bed, and two or more fingers 161 are disposed at equally spaced points intermediate of the fingers 162 and along the needle bed, the fingers 161 being used only if the machine knits wide fabric. Each of these fingers 161, 162 is releasably removably clamped to its shaft as shown, so that the fingers are non-rotatably fixed to their shafts, but can be moved therealong. Thus the fingers 162 may lie at the ends of the effective portion of the needle bed, depending on how many needles are used, according as it is desired to knit a narrow or a wide piece of fabric 100.

Since the ground weft 102 might shift along the finger 160, and might be held by the carriage 114 away from its desired proximity to the needles and to the needle bed, the fingers such as 162 are desirable to use in such a manner that they move toward the needle bed 42 and hold the ground weft 102 in close proximity thereto immediately below the needles. This positioning of the ground weft is effected as soon as the carriage 114 has laid down a length of the ground weft, and while the latter is caught by a finger 160 and is held taut by the carriage 114.

Immediately after or just as the fingers 162 thus position the ground weft 102, the fingers 161 move toward the needle bed and hold the ground weft in close proximity to the needle bed, so as to prevent any likelihood of any part of the ground weft slipping to a position above a needle in the case of a very long needle bed. When the fingers 161, 162 thus hold the ground weft, and as the needles move forward over the ground weft, the fingers 160, 161, 162 release the ground weft, which then moves under the tension of the device 104 of Fig. 18 to take up any slack in the ground weft.

The operation of these fingers 161, 162 will be more fully described hereinafter, in connection with Figs. 24A-24D, after first considering the unitary drive mechanism for the shafts 159, 163, 164.

Referring particularly to Figs. 1 and 4, there is shown a lever 166 pivoted at 167 on the frame member 26 and having a follower 168 for a cam 169 that is mounted on the shaft 130, whereby the lever is oscillated once for every six stitches performed by the machine. Connected to the upper end 170 is a rod 171 which extends toward the front of the machine, and is connected to an arm 172 that is secured to the shaft 159, all as shown in Fig. 7. Also connected to the rock shaft 159 is an arm 173, connected by a link 174 to an arm 175 which is fixed on the shaft 164. Hence the lever 166 may cause a pull on the rod 171 to rock the shafts 159, and 164. These parts may be returned to initial position by the action of a tension coil spring 176 interconnecting the lever 166 with the frame member 26.

For rocking the shaft 163, the disc 136 shown in Fig. 1, may be formed with a pair of diametrically spaced cams 177 for successively engaging one end of a lever 178 pivotally mounted at 178a on the frame member 26. Interconnecting the other end of this lever with an arm 179 fixed on the shaft 163, is a link 179a. Moving the lever 178 into engagement with the member 135 and the cams 177 is a tension coil spring 179b that interconnects the lever with the frame member 26. Since the member 135 makes one-half of a rotation for every six stitches of the machine, the fingers 161 are thus momentarily moved clockwise in Fig. 7 to the operative position shown.

It is thus noted that whereas the fingers 162 are momentarily moved counterclockwise, the fingers 161 are momentarily moved clockwise. In other words, the fingers 161 are normally in inoperative position, spaced away from the front of the needle bed. In fact, the reason for spacing the shaft 163 thereof rearward, is to cause the fingers 161 to move forward and downward to inoperative position, to thus clear the warp feeding eyes of the fingers 91.

Referring now to Figs. 24A to 24D, Fig. 24A, shows an initial position, with the hook 160 and finger 162 in respective rearward and frontward positions.

Fig. 24B shows the ground weft carrier 113 moving downward, with the hook 160 moving forward, the finger 162 moving rearward toward the needle bed, and the finger 161 being remote from the needle bed.

Fig. 24C shows the elements 160 and 162 in their operative positions, with the ground weft caught by the hook, and held down by the finger 162 in close proximity to the needle bed and just below the elevation of the needles. The yarn carrier 113 has moved upward and is beginning its travel toward the right to the other end of the machine.

In Fig. 24D, the carrier 113 having completed its travel toward the right, and being lowered and the fingers 160, 162 having released the weft 102, the movement of the fingers 161 toward the needle bed is effected. Then the fingers 161 begin their movement away from the needle bed, as soon as the needles 42 have begun to move forward to overlie the ground weft and preclude any possibility of the ground weft overlying the needles. The hook 160 has moved rearward, to release the ground weft 102, and the fingers 162 have moved forward. Due to the tension of the device 104, the ground weft moves to the right to eliminate the loop which is seen in Fig. 24C, where the ground weft was caught by the hook 160. The fingers 161 now return to initial inoperative position and the stitching proceeds, with the warp 88 passing under and catching the ground weft as suggested in Fig. 21, and as hereinbefore described.

The relation of the weft carrier 113 to the weft feeders 54 and the warp feeders 91 as well as to the fingers 160, 161, 162 will now be apparent. With the carrier 113 making its slow traverse to prevent the carriage 114 from causing vibration in the machine, the carrier 113 moves above the needles and lays down a new run of the weft 102, while five courses of stitching are being formed. This new run of weft 102 lies wholly above the needles by reason of the finger 160, see Fig. 24C. Hence there is no interference with the yarn feeders 54 and 91. In readiness for formation of the sixth run of stitching the finger 160 releases the yarn 102 and the carriage 114 is lowered, so that 75 the new run of yarn 102 drops below the needles,

and the sixth row of stitching is now formed to engage the weft 102 just laid in position. The carrier 113 is immediately elevated and the operation of the fingers in engaging the weft 102 is repeated. Thus the yarn feeders 54 and 91 are at all times clear of the carrier 113 and of the weft 102.

The jacquard control

The jacquard means is shown in part in Figs. 1, 2, 3, 7, 9, 11 and 12. It comprises an angular or square bar or shaft 180 which may be rotatable and relatively vertically movable. This jacquard bar is longitudinally grooved at 181 along each face, as clearly shown in Figs. 7 and 8, to permit jacquard pattern strips to control pins that are responsive to said strips and are adapted to enter said grooves, as hereinafter described. At its opposite ends, the bar 180 may have axial pins 182 rotatably and vertically movable in vertically slotted members 183 fixed to the frame members 26, 27, see Figs. 1 and 2.

The jacquard bar 180 is rotated one quarter turn every time that a new jacquard pattern is to be presented at the top face of the bar. In this particular machine, the jacquard bar is given a quarter turn for every six stitches or courses of the machine. To effect this motion a ratchet 184 having four equally angularly spaced teeth is provided on the jacquard bar, the teeth being successively engageable by a hook 185 fixed to a reciprocating bar or member 186, see Fig. 7. Thus a quarter turn of the jacquard bar occurs every time that the hook 185 moves to the right. When the hook 185 moves toward the left, the jacquard bar, now in elevated position, descends so that the hook engages the next succeeding tooth of the ratchet 184.

The bar 186 is slidable in a slot or guideway 187 of the frame member 26. Connected to said bar are the heads 188 which are slidable on the rails 189 fixedly mounted on the respective frame members 26, 27, see Figs. 1 and 2.

Fixedly connected to the jacquard bar 180 adjacent to each end thereof is a square block 190, adapted to rest on a pin 191 slidably mounted for vertical movement on the frame of the machine, under actuation at its lower end by an arm 192, see Figs. 1 and 4. The block 190 affords seats of large area for resting on the pins 191, and upon vertical reciprocation of the pins 191, the jacquard bar 180 is moved up and down as the case may be.

The drive for causing the vertical and rotary movement of the jacquard bar 180 will now be described. Referring to Figs. 2 and 7, the shaft 154 is seen as having thereon an eccentric 193, connected by a rod 194 to the cross head 186 to cause reciprocation of the bar 186. A similar structure is provided at the other end of the machine as shown in Fig. 1. Thus bar 186 actuates the hook 185 to turn the ratchet 184 and hence the jacquard bar 180.

To cause vertical movement of the jacquard bar, reference is had to Figs. 1 and 4, which shows the shaft 150 as having fixed thereon a cam 195 for actuating a lever 196 that is freely pivotally mounted at its lower end at any suitable point, for instance, on the shaft 130. Mounted on the lever 196 is a follower roller 197 for engagement with the cam 195. Connected to the upper end of the lever 196 is a link 198 which is also connected to an arm 199 fixed on a shaft 200 journaled in suitable brackets of the machine frame. It is thus seen that the cam 195 causes a rocking motion to be imparted to the shaft 200

5 to oscillate the arms 192 and hence to elevate the jacquard bar 180. Such movement occurs according to the shaft 150 which is actuated by the segmental gear 148 to make one rotation for every six courses or stitches of the machine.

The pin mechanism responsive to a jacquard pattern will now be described with reference to Figs. 7 and 8. Mounted on the frame members 26, 27, is a fixed cross bar 201 having a series of 10 closely spaced vertical holes therealong for vertical guiding movement in said holes of the pins 202. Extending around each pin 202 is an expansion coil spring 203 acting between the bottom of the guide bar 201 and an abutment or collar on each pin spaced above the end thereof.

Provided on the upper end of each pin 202 is 15 a head 204 having a horizontal passage for slidably mounting therein a member 205 having for ward and rearward projecting end portions. The 20 rearward projecting portion of each member 205 is engageable by the reciprocating cross bar 186 when its pin 202 is elevated. The forward end portion of each member 205 is provided with a fork at 206, so as to slidably receive an upright lever 207. This lever 207 is pivotally mounted 25 on a stationary cross bar 208, fixed on the frame members 26, 27, see also Fig. 3. The lower end of each lever 207 is pivotally connected to the link 60, see Fig. 7.

Operation of jacquard pin mechanism

It will now be understood that when a jacquard strip is placed on the jacquard bar 180, those pins 202 which are in register with the holes of the strip pass through and enter an upper groove of the jacquard bar, upon upward movement of the latter. Hence such pins 202 are not elevated but remain as shown in Fig. 7, and hence the corresponding lever 207 is not actuated, and hence the corresponding rod 55 remains engaged 30 with the front comb bar 62, so that the machine knits open work fabric. But when a pin 202 does not register with a hole in the jacquard strip, the latter elevates such pin 202 when the jacquard bar 180 moves upward. Therefore, the member 205 carried by said pin is elevated to lie in the path of the bar 186. When the latter moves forward (to the left in Fig. 7), it causes the member 205 to move forward in the head 204 35 of the pin, and hence moves the lever 207 counterclockwise. This causes the elements 55, 56, 60 to move rearward, against the tension of a spring such as 58 or 59 as the case may be, so that the weft carrier rod 55 moves from the 40 comb bar 62 into engagement with the comb bar 63. As the latter causes a travel of the weft carrier 54 past two needles, filled in sections are 45 knitted in the fabric 100 as shown.

Of course when the members 205 are not thus elevated, they can clear the bar 186 and are not affected thereby.

It will be noted that by providing a jacquard bar 180 movable toward the pins 202 as shown, the jacquard strip is not subjected to the weight 55 of the jacquard bar, and hence is not damaged, nor is there any tendency for the pins 202 to punch through the strip.

It will be understood that a complete system 60 including elements 202, 207 is provided for each and every weft carrier 54, so that the jacquard as well as the comb bars 62, 63 adapt the machine for an infinite variety of patterns, without limitation, in the sense that no repeat is necessary.

*Means for locking certain jacquard elements
in knitting filled-in areas*

It is desirable to prevent repeated movements of certain jacquard elements and parts controlled thereby to avoid unnecessary wear, and to permit the machine to operate at maximum speed. For example, the weft carrier rods 55, see Fig. 7, are normally held forward by the springs 58 or 59 as the case may be, wherever the jacquard pattern strip is perforated, and the pins 202 received in consequence in a groove 181 of the jacquard bar 180. In that case, the system remains at rest.

But where the jacquard pattern is imperforate, the pins 202 are elevated, their members 205 and levers 207 are moved, and the rods are moved against the spring tension and the rods 56 are moved from comb bar 62 to comb bar 63, moving the weft carriers rearward. At each sixth stitch or course of the machine, this entire system would move in one and in a reverse direction.

Hence a releasable locking means is provided responsive, for example, to the levers 207, desirably at the very first action of the jacquard system, to maintain the weft carriers 54 and their actuating means in rearward position in engagement with the rear comb bar 63, until a new jacquard pattern is to be presented upon the next quarter turn of the jacquard bar 180.

Accordingly a rod 209, see Figs. 3 and 7, is fixed to the frame members 26, 27 of the machine, and on this rod are freely tiltably mounted the arms or hooks 210, each adapted to individually gravitationally engage a hook or point 211 at the upper end of a lever 207.

To release the hooks 210, a means is provided shown in Figs. 7 and 9, and including a bell crank lever 212 pivotally mounted at its apex on a stub shaft 213 fixed to the machine frame. Carried by the lower arm of the lever 212 is a rod 214 underlying all of the hooks 210 and adapted to raise the same. Carried by the upper arm of the lever 212 is a rod 215 overlying the hooks 210 with ample clearance for their up and down motion. Thus the hooks 210 cannot be swung out of operable relation to the levers 207. A bell crank lever 212 may be arranged at each end of the rods 214, 215 to properly carry the same.

Referring to Figs. 2, 9 and 10, the shaft 154 is shown having a cam 216, engageable by a follower roller 216a, carried by a member 217 which is slotted at 217a to receive the shaft 154 so as to be slidably supported thereby. Extending from the member 217 is a rod 219 which is pivotally connected at 219a to the upper arm of one of the bell crank levers 212 as shown in Figs. 2, 7 and 9. In this manner, the latter is rocked once whenever the jacquard shaft 180 is ready to make a quarter turn.

It will now be clear that when a lever 207 is moved counterclockwise in Fig. 7, it is locked in that position by its hook 210, and remains so locked for six courses or stitches of the machine, whereupon the rod 214 raises the hooks and releases the levers 207, and the jacquard bar 180 makes a quarter turn to receive a different jacquard pattern.

Changeable jacquard pattern strip

In Figs. 13, 14 and 15 is shown a jacquard pattern strip or element 220, such as a strip member of any strong or metallic material so as to be adapted for long life, arranged so as to be changeable to provide any desired pattern. This is intended to be in lieu of the wasteful long sheets of jacquard paper heretofore used. Each of the

strips 220 is provided with openings or holes 221 equally spaced in like positions on all of the strips 220, so that the pins 202 are adapted to pass through all the holes of any strip. To provide the pattern effect, different holes in different strips 220 are releasably closed or blocked in any suitable manner, as by means of detachable plugs 222, all of which are identical. For example, the plugs 222 may resiliently or frictionally engage the strip 220 at the said holes, as by a press fit, and so as to be removable by the plunger of a press or in any other desired manner. To aid in positioning the plugs in the holes 221, each plug may have an annular lip or flange 223 at one end. Of course a hole 221 thus plugged is the equivalent of a blank space in a jacquard pattern, and a pin 202 is thus prevented from passing through the strip. A great many of these strips 220 may be provided, and the same are interchangeable in their order, and may be maintained in any desired sequence after being arranged. Any suitable means may be provided to removably hold a strip 220 on the jacquard bar 180.

25 *Continuous endless feeding means for jacquard strips*

In Figs. 11 to 17 inclusive is shown the mechanism for the continuous endless feeding system 30 for a jacquard pattern means, such as the strips 220, according to one possible embodiment of the invention.

Thus the strips 220 may each have at its opposite ends the open slots 224, and may have its 35 opposite edges adjacent to each slot beveled at 225, for purposes hereinafter described.

Mounted on the frame members 26, 27 is a 40 fixed frame member 226. Mounted on the latter are the spaced brackets 227, which provide bearings for a shaft 228, and each having three angularly spaced arms 227a to fixedly support a pair of track members or guides 229. Each of the latter is relatively thin so as to be adapted to guidingly engage in the slots 224 of the strips 45 220. The guides 229 are of like shape and arrangement, each having a semicircular section, an upper section 229a leading to a side of the jacquard bar 180 in horizontal alignment with the axis thereof, and a lower section 229b, leading in a partly curved downward incline from the lower face of the jacquard bar 180. In general, the arrangement is such that the strips 220 travel in a counterclockwise circuit in Fig. 12, being supplied to the right side of the jacquard bar, 50 and later moved to operative top position when the jacquard bar makes a counterclockwise quarter turn, then retained on the opposite side of the jacquard bar when the latter makes the third quarter turn, and finally discharged down the 55 incline 229b when the jacquard bar makes the fourth quarter turn so that the strip 220 is on the downward face of said bar. The guides 229 may be reenforced in any suitable manner.

In order to feed the strips 220 from the lower 60 to the upper portion of the guide 229 a pair of arms 230 are fixed to the rock shaft 228 so as to be oscillated thereby through an angle of about 180 degrees. When the arms 230 extend toward the left in Fig. 12, they permit a strip 220 to pass thereunder. When they move toward the right, they raise that strip 220 to the point where a catch 231 locks under the said strip and prevents it from falling back. Catch 231 is adjustable according to the number of pattern strips.

This catch 231 is shown in Figs. 11 and 17 as being pivotally mounted at 232 on a plate fixed on the guide 229 and extending parallel to the plane of the flat face thereof. A tension coil spring 234 is connected to the plate 233 and to a lug on the catch 231 so as to swing the catch counterclockwise in Fig. 17. As the catch is offset from the slot 224 it will be free of the same. When a strip 220 is moved upward by the arms 230 from the dot dash line position of Fig. 17 to the full line position, the ends of the strip bear against the opposed catches 231 on the spaced guides 229, and ride upward along the inclines of the catches, tilting the latter until caught by the catches that are actuated by their springs 234. By providing a continuous stack of the strips 220, the same are thus pushed forward all along the guides 229 into proximity to the jacquard bar 180.

To rock the shaft 228 which carries the arms 230, reference may be had to the structure of Figs. 4, 11 and 12, wherein the shaft 130, which turns at a suitable speed, rotates an eccentric 235, connected at 236 to a rack bar 237 for turning a pinion 237a fixed to the shaft 228. A guide shoe 238 hung from the shaft 228 is provided for the rack bar to keep it in engagement with the pinion 237a.

In order for the jacquard bar 180 to receive a strip 220, the said bar is provided at each face 30 with end projections 239 adapted to enter the slots 224 of said strips. These projections extend into close proximity to the ends 240 of the upper sections 229a of the guides 229, and thus the rotation of the jacquard bar is not interfered with.

To feed the jacquard strips 220 one by one to the ends of the guide sections 229a, each of the latter is provided with a rotary bladed or propeller element 241 carried by a shaft 242 suitably mounted on its respective guide section 229a. For actuating said shafts 242, each is provided with a worm wheel 243, see Fig. 12, driven by a worm 244. Both worms 244 are on a shaft 245 suitably mounted on the guides 229.

For rotating the shaft 245, a pinion 246, see Figs. 4, 11 and 12, is driven by the segmental gear 148, so as to make one rotation every time the jacquard bar makes a quarter turn. This pinion 246 is on a shaft 247 mounted on a bracket 50 248 carried by the frame member 226. Also mounted on the shaft 247 is a sprocket wheel 249 connected by a sprocket chain 250 with a sprocket wheel 251 fixed on the shaft 245.

It will be noted that by reason of the beveled edges 225 of the jacquard strips 220, the propellers 241 have no difficulty in engaging a single jacquard strip 220. At the same time the propellers serve the function of holding back the remaining strips 220.

When once a jacquard strip 220 has thus been moved forward by the propellers 241, it is desirable to lock the same on the jacquard bar 180 against accidentally dropping off as the latter continues its rotation. Hence a releasable locking device or spring catch 252 shown in Figs. 11 and 16 is utilized, identical devices being provided for each end of each jacquard bar face 180. A description of one such structure adjacent to one propeller 241 will apply also to the other. Each device 252 comprises four stationary plates, 253, each secured to one face of the jacquard bar 180 and overlying the groove 181, so as to close the same except at the ends of the groove. One end of each groove 181 is closed by a sta-

tionary abutment 254. Mounted in each groove so as to be slidably retained therein by a plate 253 is a member 255, which is sufficiently undercut to lie below the abutment 254 and to afford space for an expansion coil spring 256 which acts between an abutment 254 and a shoulder of the member 255. The opposite end portions of each member 255 project beyond a plate 253 and outward of the groove 181 to afford at one end a hook or catch 239, hereinbefore described, and at the other end a toe portion 257. It is noted that the catch portion is formed with a cam shaped nose so that when a jacquard strip 220 is fed to the jacquard bar, the strip 220 rides at its end along the cam nose and presses the members 255 apart against the tension of the springs 256. To apply sufficient pressure to the jacquard strips 220 to overcome the pressure of the springs 256, angle rods 258, see Fig. 7, are fixed to the cross bar 186 so that when the latter moves forward, with the jacquard bar 180 elevated to raise a strip 220 on the guide 229, the rods 258 are moved forward to press such elevated strip 220 to be hooked by the catches 239. It will be understood that the elevated jacquard strip, before being locked by the catches, is carried at its slots 224 by the rearward projecting ends of the catches 239.

To release the catches 239 when they lie at a bottom face of the jacquard bar 180, a cam 259 is provided. These cams are mounted on a rock shaft 260 carried in brackets 261 fixed to the stationary bar 208. Attached to the shaft 260 is an arm 262 to which is pivotally connected a rod 263 having at its remote end a slotted portion 264, through which the shaft 130 extends to slidably support said portion. The latter has follower engagement with a cam 265 fixed on the shaft 130.

Operation of endless feed jacquard system

In describing the operation, it will be best to revert to the motion of the jacquard bar 180. That motion occurs in this particular embodiment once every six courses or stitches of the machine. The motion consists of an up and down movement followed by a quarter turn of the jacquard bar.

Before the jacquard bar 180 moves upward, the propellers 241 move forward a jacquard strip 220 so that it laterally rests on the catches 239 which extend into the slots 224 of said strip. Now the jacquard bar 180 moves upward, and the laterally held strip 220 is pushed into snap engagement with the catches 239 by the angle rods 258 carried by the cross bar 186, see Fig. 7, which moves toward the jacquard bar. (During this upward movement, a jacquard strip 220 on the top face of the jacquard bar causes actuation 60 of the pins 202.) Now the jacquard bar 180 moves downward so that its ratchet 184 engages the hook 185 carried by said cross bar 186. As the latter moves away from the jacquard bar 180, the hook 185 causes a quarter turn of the jacquard bar. Thus the jacquard strip 220 that was laterally held is now at the top face of the jacquard bar, and is idle while the machine proceeds to make six stitches according to the jacquard pattern as determined by the previous jacquard strip, which is now in an inoperative position at the front or opposite side of the jacquard bar. Thus the cycle proceeds.

When a jacquard strip 220 finally reaches the underside of the jacquard bar, the cams 259 engage the toes 257 of the lowermost catches 239

which hold said strip and move said catches apart to release said strip, which thereupon moves downward along the catches in its slots 224 until the inclined guide section 229b engages in said slots.

Then the oscillatory arms 230 move this jacquard strip upward until it is caught by the catches 231, whereby the stack of said strips is gradually fed toward the propellers 241 to provide the continuous, endless cycle.

Take-up means for the knitted fabric

The take-up means for the knitted fabric is shown mainly in Figs. 1 and 3, and in part in Fig. 2. It includes a pair of rolls 266, 267 at the front of the machine, and a pair of rolls 268, 269 at the rear of the machine, of which the rolls 266 and 268 are idlers. All of these rolls are mounted on the frame members 26, 27, the fabric 261a passing under and around the roll 267, then between the rolls 266, 267, over the roll 266 and thence around the roll 269, with the roll 268 acting as a follower weight.

To drive the roll 267, a gear 270 is connected to its shaft. This gear engages a pinion 271 on a stub shaft fixed on the frame member 26, and having a gear 272. The latter engages a pinion 273 on a stationary stub shaft 274 fixed to the frame member 26, and carrying a ratchet wheel 275. The latter is provided with a pawl 276 pivotally mounted on an arm 277 which is pivotally mounted on the stub shaft 274. To oscillate said arm 277, a cam 278 is mounted on the shaft 73, said cam having follower engagement with a rod 279, slidably mounted with necessary clearance in a guide 280 of the frame member 26, so that the rod is vertically reciprocable to impart a very small oscillatory movement to the arm 277 to which its lower end is pivotally connected at 281.

It will thus be clear that the shaft 73 causes oscillation of the arm 277 so that the pawl rotates the ratchet wheel 275 to operate the gear train 270-273 to turn the roller 267.

Reverse motion of the ratchet wheel is prevented by a spring pawl 282 engaging the same and mounted on the frame member 26.

To limit the travel of the pawl 276, an arm 283 may be fixed to the stationary shaft 274 and may have a set screw 284 adapted to abut the arm 277 to limit the oscillation thereof, whereby the pull on the knitted goods is adjustable.

The idler roller 266 is desirably mounted on a pair of arms 285 pivotally mounted on the machine frame, said arms being actuated by tension coil springs 286 to resiliently urge the roller 266 against the roll 267.

At the other end of the machine, see Fig. 2, a sprocket wheel 287 is connected by a chain 288 with a sprocket wheel 289 that is connected to the roller 269. For the idler roller 268, a guide-way 290 is provided to permit the same to move upward as the fabric accumulates on the roller 268.

It will be understood that the sprocket wheel 289 may have any suitable slip or frictional engagement with the roller 269 to allow for increase in the diameter of the roll of knitted goods.

Resume—General operation of the machine

As shown in Fig. 23, the fabric 100 is knitted with open spaces and with filled-in weft areas 99, there being a ground or cable weft 102 which is preformed and serves as a reinforcement.

Referring to Fig. 7, the weft 49 is supplied to 75

the needles by the carriers 54, the warp by the fingers 91, and the ground weft by the carrier 113 of the carriage 114.

To afford infinite variety of pattern, the weft carrier rods 55 are engageable with the comb bar 62 for the ordinary stitch as at 84, and with the comb bar 63 for a filled-in knitting 99, that is past a pair of needles, see Fig. 8. These weft carrier rods are individually engageable with either comb bar in any desired order or arrangement, and each comb bar has its individual path of motion. For moving the rods to and fro between the comb bars, a jacquard system is utilized.

15 Since the machine is designed to make six stitches for any given jacquard pattern section, the jacquard system, see Figs. 7 and 8, is releasably locked, as at 207, 210, in respect to elements which control the weft carrier rods 55 engaged by the comb bar 63, against the tension of springs 58, 59 tending to move said rods into engagement with the comb bar 62. Hence needless reciprocation of elements and wear on the machine are avoided.

25 By using jacquard strips 220 having releasably closed holes, see Figs. 13 to 15, the same elements can be repeatedly employed for different patterns. A further advantage is that a continuous endless feed system can be provided for these strips as shown in Figs. 11 and 12. Thus the strips 220 follow the guides 229 to be fed to the jacquard bar 180 and then to be returned to the guides, all as hereinbefore in detail described. It will suffice to briefly mention that oscillatory arms 230 move the strips from a lower to a higher section of the guides, at which they are held against return by catches 231; the propellers 241 engaging the beveled parts 225 of the strips to move the strips onto catches 239 on the jacquard bar, which catches are releasable by the cams 259.

We claim:

1. A device including a jacquard knitting machine comprising a needle bed having hooked needles, means for feeding warp yarns to the needles, individual elements for the needles for laying weft yarns into the hooks thereof, means for projecting the needles outward of the needle bed and for retracting the needles, including means for retarding retraction of the needles at a point in the travel of the needles, while the weft yarn is being laid in the hooks thereof, and means for causing operation of said elements during the retardation in the retraction of the needles.

2. A device including a jacquard knitting machine comprising a needle bed having therein hooked needles movable inward and outward of the bed, yarn feeding means for the needles including elements for laying weft yarns in the individual hooks of the needles, said elements being adapted to travel at a greater elevation than the needles, means for causing a retarded retraction of the needle at a point in the travel thereof to afford time for laying the weft into the needle hooks, and means for causing operation of said elements during the retardation in the retraction of the needles.

3. A device including a jacquard knitting machine comprising a needle bed having therein needles provided with hooks and tongues therefor, a first means for laying warp yarns in the hooks, a second means for laying weft yarns in the hooks, a third means for advancing and retracting the needles, coordinated with the first and second means so as to advance the needles to cause the

warp yarn to pass over and drop below the tongues externally of the hooks and then retract the needles with a momentary retardation to cause the needle hooks to receive the weft yarns, the third means then causing retraction of the needles for forming a knot between said yarns, the third means then advancing the needles so that the knots drop back of the needle hooks, the third means then causing retraction of the needles so that the knot moves the tongue to closed position and casts off from the needle.

4. A device including a knitting machine having a needle bed having needles therein, means co-operating with the needles for the knitting operation of the needles, said means including members comprising individual yarn carrying elements for the needles, a jacquard for causing movement of selected members to one operating position, upon each stitching operation of the needles, means for periodically changing the setting of the jacquard after the needles have caused the knitting of a plurality of stitches, locking means to lock said selected members in said operating position, means to cause release of the locking means only upon a change in setting of the jacquard, and means to cause the yarn carrying elements to have different operating movements in response to said members.

5. A device including a knitting machine comprising a jacquard, means for causing the jacquard to control in part the successive stitching operations of the machine and for changing the setting of the jacquard after a plurality of stitching operations, including individual control elements coacting with the needles, and individual releasable means for locking certain of said elements in a position to which they would otherwise be caused to be repeatedly moved by the jacquard, during a given setting of the jacquard, and common means for releasing the individual releasable means upon a change in the setting of the jacquard.

6. A device including a knitting machine comprising a jacquard bar, a carrier bar generally parallel thereto, means to cause relative movement between the said bars toward and away from each other upon each stitching operation, controlling members coacting with the individual needles, comprising elements mounted on the carrier bar individually responsive to a jacquard pattern of the jacquard bar so that the different elements assume different elevations, and an actuator bar generally parallel to the first mentioned bars, the latter and the actuator bar being relatively movable toward and away from each other so that the actuator bar actuates those elements which have a given elevation and clears those elements which have a different elevation.

7. A device including a knitting machine comprising a jacquard bar, a carrier bar generally parallel thereto, means to cause relative movement between the said bars toward and away from each other upon each stitching operation, controlling members coacting with the individual needles, comprising elements mounted on the carrier bar individually responsive to a jacquard pattern of the jacquard bar so that the different elements assume different elevations, and an actuator bar generally parallel to the first mentioned bars, the latter and the actuator bar being relatively movable toward and away from each other so that the actuator bar actuates those elements which have a given elevation and clears those elements which have a different elevation, and means for releasably locking portions of those

controlling members that are actuated by the actuator bar while the jacquard pattern remains the same.

8. A device including a knitting machine comprising a jacquard means, individual controlling elements coacting with the needles of the machine, said elements being responsive to a pattern of the jacquard to be moved so that different elements occupy relatively advanced and retracted position upon actuation by the jacquard, means yieldingly urging the elements to move to retracted position, and means for releasably locking in set position those elements which have been moved to the advanced position, while the jacquard pattern remains unchanged, to thus avoid repeated movement of such elements upon each stitching operation of the machine.

9. A device including a knitting machine having a needle bed having reciprocating hook-and-latch needles therein, individual upright weft carrying elements each of which is individually movable to and fro to lay a weft across one needle or across a plurality of needles, said elements being individually movable back and forth to different positions along a needle, means for causing movement of the elements to said different positions, and actuator means for moving the elements in one of said positions with each element moving past one needle, and for moving the remaining elements with each element moving past a plurality of needles, whereby filled-in and open-work fabric portions can be knitted according to a desired pattern, means for feeding warp yarns to the needles, and means coacting with the needles for laying another weft yarn across all the needles, means for periodically actuating the last named means after the needles have made a plurality of stitches, the first named means including a jacquard means and individual control elements for the weft carrying elements, and means for releasably locking certain of said control elements to maintain selected weft carrying elements in a required position during the period mentioned.

10. A knitting machine including a jacquard system therefor, comprising a series of different pattern controlling jacquard sections, and means for feeding the latter in a continuous recurrent cycle, including means for operatively positioning a section relative to a jacquard responsive device of the machine and for thereafter removing said section from operative relation to said device, the last mentioned means including a carrier intermittently angularly movable about its longitudinal axis, said carrier having means at different sides thereof for engaging a plurality of jacquard sections to lie at different sides thereof, and means for actuating said carrier.

11. A knitting machine including a jacquard system having jacquard pattern strip members, means responsive to said strip members for controlling the knitting of the machine, a rotary jacquard bar, and feeding means for successively actuating the strip members in a predetermined sequence, including means for removing a strip member from the jacquard system and disposing the strip member on the jacquard bar, in operative relation relative to said responsive means, said jacquard bar being bodily movable relative to the responsive means, and means for receiving the strip member from the jacquard bar, whereby a row of the strip members is maintained so that the strip members are taken from one end of the row and returned to the other end thereof, said feeding means being constructed to cause

a continuous recurrent cycle of feed of the strip member.

12. A knitting machine including a jacquard system, comprising a series of jacquard pattern controlling sections, a rotatable support with which the jacquard sections are successively engageable, a relatively stationary support for the jacquard sections terminating at angularly spaced points of the rotatable support and forming with the latter a continuous path for the jacquard sections, means for causing the latter to successively advance from the stationary support into engagement with the rotatable support, and means for causing intermittent rotation of the latter for a predetermined angle so that the jacquard sections are moved by the rotatable means from operative to inoperative position to be thence discharged onto the stationary support.

13. A knitting machine including a jacquard system comprising a series of strips each constituting a pattern control element for a certain knitting operation of the machine, different strips being presented for the successive knitting operations of the machine, a jacquard bar intermittently rotatable for a given angle upon completion of each said knitting operation of the machine, said bar and said strips having releasable interengaging means at different faces of said bar, a first means for feeding said strips to said bar, a second means for receiving said strips from said bar, the first and second means being angularly spaced and being adapted for substantially simultaneous operation so that said bar receives a strip at one face and discharges a strip at another face thereof, and curvilinear guide means for said strips extending between the said first and second means to permit the strips to be returned from the first means to the second means.

14. A knitting machine according to claim 13, wherein the said first means includes an intermittent rotatable arm for moving said strips along said curvilinear path, and automatic means to lock said strips against reverse movement along said path.

15. A knitting machine comprising a jacquard system having a member having a series of spaced openings, yarn feed controlling means comprising pins adapted to register with said openings, and detachable means mounted on said member for closing certain selected openings to cause the knitting of a desired pattern, whereby the same member can be used as a control for the knitting of different patterns, said member having an inclined edge, and means for feeding said member to operative position comprising a rotor engageable with said inclined edge to separate the member from a stack of said members.

16. A knitting machine having a jacquard system comprising strips having holes therein, means controlling yarn carriers and having upright pins adapted to enter said holes, an intermittently angularly movable jacquard carrier bar to hold a strip in operative position, guide means providing an endless path along which said strips are movable toward and from said jacquard bar in parallel relation thereto, the jacquard bar having projecting holding elements at different sides thereof engageable with said strips, means for feeding a strip from the guide means into initial engagement with the projecting means, means for causing a relative upward movement of the jacquard bar to relatively raise the engaged strip, means for moving said strip toward the jacquard bar into full engagement therewith and for rotating said jacquard bar to move said strip into

angularly spaced relation to said guide means for operative coaction with said pins, and means for causing release of said strip from the jacquard bar upon a further angular movement of the latter to cause said strip to return to said guide means.

17. A jacquard knitting machine having knitting means, including a needle bed having needles therein, means to actuate the needles, means including a carriage traveling along the needle bed from end to end thereof for laying down a ground weft over the needles, means to cause a single traversing movement of the carriage for every series of stitches formed by the needles, with said movement occurring continuously during formation of said series of stitches, and means to cause the ground weft to be lowered below the needles after completion of the traverse, whereby the ground weft is caught in the stitches to thus produce a fabric having open spaces bridged by the ground weft.

18. A knitting machine having a bed having knitting needles, individual yarn feeding elements for the needles movable selectively past a single needle or past a plurality of needles, means for causing movement of said elements in operative relation to the needles, including members extending along the needle bed selectively engageable with said elements so that one of the members moves its elements past one needle and the other member moves its elements past a plurality of needles, means for causing reciprocation of said members along the needle bed, and means for causing selective engagement between said elements and said members, comprising selector portions for the different elements, said selector portions being mounted on said members for movement therewith, said elements being vertically movable to positions above the needles, and means for causing the vertical movement of said elements with at least one row of the elements being moved to a position below the needles.

19. A knitting machine comprising a needle bed having needles therein, yarn feeders for the individual needles, said yarn feeders being reciprocable selectively past one needle or past a plurality of needles, said yarn feeders being selectively movable in the direction of the length of the needles to a first or to a second yarn feeding position so that yarn feeders moving past a plurality of needles shall not interfere with yarn feeders moving past a single needle, with the yarn feeders in both positions being vertically movable to positions above the needles, automatic selective means for actuating the yarn feeders, and means for causing vertical movement of the yarn feeders to positions above and below the needles.

20. A knitting machine including a needle bed having needles therein, a vertically reciprocable means elongated along the needle bed, yarn carriers for the needles mounted on said means for individual selective movement transversely of said means to different yarn feeding positions relatively to the needles, means for actuating the reciprocable means, means for causing said selective movement of the yarn carriers, a plurality of elongated members horizontally reciprocable along the needle bed, the yarn carriers being movable with one of the other of said members according to said selected yarn feeding positions of the carriers, means mounted on the reciprocable means and movable to actuate said members to cause one of the members to move its yarn carriers past a single needle and to cause the other member to move its yarn carriers past a plu-

rality of needles, and means mounting the different yarn carriers on the reciprocable means for movement about individual axes to permit movement of the yarn carriers by one or another of said members.

21. A knitting machine including a needle bed having needles therein, yarn carriers for the needles mounted for selective movement to different yarn feeding positions for selective movement past one needle or past a plurality of needles according to the yarn feeding positions of the carriers, means mounting the yarn carriers for individual motion thereof to said different positions including motion of the individual yarn carriers past one or more needles, and means for selectively actuating the yarn carriers to said different positions and to cause the same to feed yarn past one or more needles, said mounting means being vertically movable to raise the yarn carriers above the needles for the movement past the same and to lower the yarn carriers below the needles upon retraction of the needles, and actuator means for the mounting means.

22. A knitting machine including a needle bed having reciprocable needles therein, yarn carriers for the needles, movable past the same above the needles, said carriers being selectively reciprocable in course of operation of the machine so that certain of them move past a single needle and others move past a plurality of needles for knitting open closed fabric sections, and means for selectively actuating the carriers to cause said motions of the carriers including a relative motion between the different selected carriers along the upright longitudinal planes of the needles to different yarn feeding positions to prevent interference between carriers that move past a single needle with those that move past a plurality of needles, said yarn carriers being vertically movable to positions above and below the needles, means for projecting and for retracting the needles coordinated with said actuating means, the means for actuating the carriers causing said movement past a plurality of needles only after substantially complete retraction of the needles, and means coordinated with said actuating means for causing the vertical movement of the yarn carriers.

23. A knitting machine including a needle bed having reciprocable needles therein, yarn carriers for the needles, said carriers being selectively reciprocable so that certain of them move past a single needle and others move past a plurality of needles for knitting open and closed fabric sections, and means for selectively actuating the carriers to cause said motions of the carriers including a relative motion between the different selected carriers along the upright longitudinal planes of the needles to different yarn feeding positions to prevent interference between carriers that move past a single needle with those that move past a plurality of needles, carriage means adapted to travel back and forth along the needle bed for laying down a ground weft over the needles, means cooperating with the carriage means for lowering the ground weft below the needles, and means to cause the carriage means to function at intervals during which the machine performs a plurality of stitching operations.

24. A knitting machine including a needle bed having reciprocable needles therein, yarn carriers for the needles, said carriers being selectively reciprocable so that certain of them move past a single needle and others move past a plurality of

needles for knitting open and closed fabric sections, and means for selectively actuating the carriers to cause said motions of the carriers including a relative motion between the different selected carriers along the upright longitudinal planes of the needles to different yarn feeding positions to prevent interference between carriers that move past a single needle with those that move past a plurality of needles, said actuating means causing the selected position of the carriers to be maintained for an interval during which the machine performs a plurality of knitting operations, said actuating means including a jacquard means for causing operation of said carriers, and means to cause the carriers to maintain the selected positions in stationary condition during said interval independently of said jacquard means, with the latter operating upon each knitting operation of the machine.

25. A device including a knitting machine having a needle bed having reciprocatory hook-and-latch needles therein, individual upright yarn carrying elements each of which is individually movable to and fro to lay a yarn across one needle or across a plurality of needles, said elements being individually movable back and forth to different positions along a needle, means for causing movement of the elements to said different positions, and actuator means for moving the elements in one of said positions with each element moving past one needle, and for moving the remaining elements with each element moving past a plurality of needles, whereby filled in and open work fabric portions can be knitted according to a desired pattern, said actuator means comprising a plurality of comb-like bars longitudinally individually reciprocable along different paths to actuate the elements, the elements in one of said positions being engageable by the teeth of one bar, and the elements in another position being engageable by the teeth of the other bar, said means for causing movement of said elements to different positions along a needle comprising a jacquard system operating at intervals during which the machine makes a plurality of stitches, means separate of the jacquard system for yieldingly moving all the yarn carrying elements into engagement with one of the comb-like bars, with the jacquard system moving selected yarn carrying elements into engagement with the other comb-like bar against the force of the yieldingly moving means, and means for releasing locking during said interval the yarn carrying elements thus actuated by the jacquard system.

26. A knitting machine including a needle bed having upwardly hooked needles, yarn carrying elements therefor operable to move past a single needle to lay yarn into the hook thereof and past a plurality of needles to lay yarn thereunder in the knitting of open and closed fabric sections, means for projecting the needles outward of the needle bed and for retracting the needles, including means for retarding retraction of the needles at a point in the travel of the needles while the yarn is being laid into the hooks thereof, and means for causing operation of the said elements during the retardation in the retraction of the needles.

27. A knitting machine comprising needles, members cooperating therewith for knitting operation, jacquard elements responsive thereto so that the elements selectively assume relatively advanced and retracted positions, a common movable means for those elements that are in the

advanced position, the different elements having movable portions such that said portions lie in the path of movement of said common means in the advanced position of the elements to cause movement of said portions to move said members to an operating position, means to releasably lock said members in said operated position, said members being yieldingly urged away from said operated position, and means to actuate said jacquard means for each stitching operation of the machine and to cause the jacquard means to maintain its setting for a plurality of knitting operations of the machine.

28. A knitting machine comprising needles, members cooperating therewith for knitting operation, jacquard elements responsive thereto so that the elements selectively assume relatively advanced and retracted positions, a common movable means for those elements that are in the advanced position, the different elements having movable portions such that said portions lie in the path of movement of said common means in the advanced position of the elements to cause movement of said portions to move said members to an operating position, said common means being separate of the elements.

29. A knitting machine comprising needles, members cooperating therewith for knitting operation, jacquard elements responsive thereto so that the elements selectively assume relatively advanced and retracted positions, a common movable means for those elements that are in the advanced position, the different elements having movable portions such that said portions lie in the path of movement of said common means in the advanced position of the elements to cause movement of said portions to move said members to an operating position, and means yieldingly urging said members away from the operated position in opposition to said common means.

30. A knitting machine having a needle bed having knitting needles, weft carriers for the needles, rods pivotally mounting the individual carriers for selective movement past one or more needles, vertically movable means slidably mounting said rods to permit the carriers to move in the longitudinal direction of the rods to different yarn feeding positions, means to cause selective movement of the carriers to the different yarn feeding positions, and means to cause the yarn carriers in the different positions to respectively move past different numbers of needles.

31. A knitting machine including a jacquard system comprising jacquard strip members, a guide means for a stack of said members, said members being removable from the guide means, and rotary blade means having a pitch such that the blade means shall engage a single member and propel the same forward along the guide means upon rotary movement of the blade means.

32. A knitting machine including a jacquard system comprising jacquard strip members, a movable carrier for a strip member, and means for releasably locking the member to the carrier, said means comprising a spring catch on the carrier for engaging said member, said spring catch having a cam portion actuated by the member upon movement of the latter onto the carrier, and means for moving the member onto the carrier for engagement with said cam portion.

33. A knitting machine including a jacquard system comprising jacquard strip members, a movable carrier for strip member, and means for releasably locking the member to the carrier, said

means comprising a spring catch on the carrier for engaging said member, said spring catch having a cam portion actuated by the member upon movement of the latter onto the carrier, and means for moving the member onto the carrier for engagement with said cam portion, said cam portion and said strip member having parts having male and female interengagement so that the cam portion supports the strip member as the latter moves from the moving means into engagement with the catch.

34. A knitting machine including a jacquard system having strip members having end slots, a carrier, a guide means for moving the strips to said carrier, said guide means having guide portions slidably engaged in said slots, the carrier having engaging elements for releasably locking the jacquard strips thereon, said elements having projections engageable in said slots to support the members as they move from the guide means onto the carrier.

35. A knitting machine including a jacquard system having a plurality of jacquard strips, a guide for the members terminating in spaced ends providing strip discharging and strip receiving stations respectively, a jacquard responsive means, a carrier having an operating position at which the carrier is adapted to receive a strip at the discharging station, said carrier being movable to cause said strip to operate the jacquard responsive means and being then returnable to said operating position, said carrier being rotatable in said operating position to bring the strip to the said receiving station, means to cause movement of the strips along the guide and to actuate the carrier and means mounted on the carrier for releasably locking said strips.

36. A knitting machine having a jacquard system having a jacquard responsive means, a plurality of jacquard strips, and means for feeding said strips in a circuit, comprising a guide having a strip discharging point and a strip receiving point spaced therefrom, and a strip carrier intermittently angularly movable about its longitudinal axis and being in proximity to said points of the guide and cooperating with the latter to receive a strip at said discharging point of the guide, said carrier being angularly movable to bring the strip into alining position with the jacquard responsive means, said carrier being then angularly movable to bring said strip to the receiving point of the guide, means to cause said angular movement of the carrier and to cause the jacquard responsive means to be actuated by a strip in the said alining position of the strip, and means to cause the strip to move along the guide and onto the carrier with the strip returning thence to the guide to complete the circuit.

37. A knitting machine including a jacquard system having jacquard pins responsive to a jacquard pattern element so that said pins assume relatively advanced and retracted positions by pressure of the pins against said pattern element, members movably carried by the individual pins so that said members assume correspondingly advanced and retracted positions, and a common means adapted to aline only with those members which are in one of said positions for actuating said members for a powerful jacquard control action without requiring increased pressure of pins against the pattern element, and means for causing operation of said common means to cause relative movement between the pins and their members that are in said position of alinement with the common means.

38. A knitting machine including a jacquard sys-

tem having jacquard pins responsive to a jacquard pattern element so that said pins assume relatively advanced and retracted positions by pressure of the pins against the pattern element, knitting means comprising elements responsive to the jacquard system, members responsive to said pins and adapted to assume relatively advanced and retracted positions, said members being adapted to cause movement of their respective elements of the knitting means, a common actuator means separate of the members and adapted to engage only those members which are in one of said positions for powerfully actuating such members to cause movement of corresponding elements of the knitting means, and means for causing operation of the common means upon movement of members to the said one of said positions.

39. A jacquard knitting machine including a needle bed having reciprocatory needles therein, a reciprocatory carriage for laying down a ground weft along the needle bed, means for vertically reciprocating the carriage at each end of the needle bed, releasable guide means for the ground weft at each end of the needle bed cooperating with said carriage and the first mentioned means to cause the ground weft to be carried across the needle bed above the needles and to cause the ground weft to drop below the needles when the carriage is lowered at one end of the needle bed and the guide means simultaneously releases the ground weft at the other end of the needle bed, whereupon the carriage is elevated and the adjacent guide means engages the ground weft with the carriage beginning another traverse, holding means operative as the guide means releases the ground weft, said holding means being located wholly below the needles and serving to hold the ground weft against the needle bed immediately below the needles and while the needles are being projected to thus prevent the ground weft from slipping upward over the needles, said holding means being located at a point intermediate of the ends of the needle bed, and means for actuating said holding and guide means.

40. A jacquard knitting machine including a needle bed having reciprocatory needles therein, control means for a ground weft for laying down the ground weft above the needles while the needles are projected and for causing the stretch of ground weft to be lowered below the needles while the same are in relatively retracted position so that the ground weft lies in operative relation immediately below the needles, means operative after the operation of the control means to engage the ground weft and to hold it closely to the needle bed to prevent the ground weft from accidentally moving upward over the needles, and means for actuating said control means and the second mentioned means.

41. A jacquard knitting machine including a needle bed having reciprocatory needles therein, control means for a ground weft for laying down the ground weft above the needles while the needles are projected and for causing the stretch of ground weft to be lowered below the needles while the same are in relatively retracted position so that the ground weft lies in operative relation immediately below the needles, means operative after the operation of the control means to engage the ground weft and to hold it closely to the needle bed to prevent the ground weft from accidentally moving upward over the needles, and means for actuating said control means and the second mentioned means, the second

mentioned means being located wholly below the needles, the control means being operative to hold the ground weft at an end of the needle bed, and the second means being located intermediate of the ends of the needle bed.

42. A knitting machine comprising a needle bed having needles, means for projecting and retracting the needles, means for feeding weft yarns to the needles comprising weft guides for the individual needles selectively movable into a first row and a second row, said weft guides and the needle bed being reciprocable relative to each other along the needle bed with each of the weft guides in the first row being movable past a single needle and each of the weft guides in the second row being movable past a plurality of needles, means for causing said selective movement during operation of the machine, actuator means for causing the reciprocatory movement of the first and second rows, said actuator means including different movable means for the different rows such that the weft guides in course of selective movement between said rows move into engagement with the said different means during the operation of the machine, said weft guides being vertically movable to positions above the needles, and drive means to cause said vertical movement of the weft guides so that the movement of said rows past the needles occurs above the needles.

43. A knitting machine comprising a needle bed having needles, means for projecting and retracting the needles, means for feeding weft yarns to the needles comprising weft guides for the individual needles selectively movable into a first row and a second row, said weft guides and the needle bed being reciprocable relative to each other along the needle bed with each of the weft guides in the first row being movable past a single needle and each of the weft guides in the second row being movable past a plurality of needles, means for causing said selective movement during operation of the machine, actuator means for causing the reciprocatory movement of the first and second rows, said actuator means including different movable means for the different rows such that the weft guides in course of selective movement between said rows move into engagement with the said different means during the operation of the machine, said weft guides being vertically movable to positions above the needles, and drive means to cause said vertical movement of the weft guides so that the movement of said rows past the needles occurs above the needles and while the needles are being retracted.

44. A knitting machine comprising a needle bed having needles, means for projecting and retracting the needles, means for feeding weft yarns to the needles comprising weft guides for the individual needles selectively movable into a first row and a second row, said weft guides and the needle bed being reciprocable relative to each other along the needle bed with each of the weft guides in the first row being movable past a single needle and each of the weft guides in the second row being movable past a plurality of needles, means for causing said selective movement during operation of the machine, actuator means for causing the reciprocatory movement of the first and second rows, said actuator means including different movable means for the different rows such that the weft guides in course of selective movement between said rows move

into engagement with the said different means during the operation of the machine, said weft guides being vertically movable to positions above the needles, and drive means to cause said vertical movement of the weft guides so that the movement of said rows past the needles occurs above the needles, said actuator means causing movement of the said second row of weft carriers past their needles only after the needles have been substantially wholly retracted.

45. A knitting machine comprising a needle bed having needles, means for projecting and retracting the needles, means for feeding weft yarns to the needles comprising weft guides for the individual needles selectively movable into a first row and a second row, said weft guides and the needle bed being reciprocable relative to each other along the needle bed with each of the weft guides in the first row being movable past a single needle and each of the weft guides in the second row being movable past a plurality of needles, means for causing said selective movement during operation of the machine, actuator means for causing the reciprocatory movement of the first and second rows, said actuator means including different movable means for the different rows such that the weft guides in course of selective movement between said rows move into engagement with the said different means during the operation of the machine, said weft guides being vertically movable to positions above the needles, and drive means to cause said vertical movement of the weft guides so that the movement of said rows past the needles occurs above the needles, said drive means causing downward movement of all of the weft carriers simultaneously only after the needles have been substantially wholly retracted.

46. A knitting machine comprising a needle bed having needles, means for projecting and retracting the needles, means for feeding weft yarns to the needles comprising weft guides for the individual needles selectively movable into a first row and a second row, said weft guides and the needle bed being reciprocable relative to each other along the needle bed with each of the weft guides in the first row being movable past a single needle and each of the weft guides in the second row being movable past a plurality of needles, means for causing said selective movement during operation of the machine, actuator means for causing the reciprocatory movement of the first and second rows, said actuator means including different movable means for the different rows such that the weft guides in course of selective movement between said rows move into engagement with the said different means during the operation of the machine, said weft guides being vertically movable to positions above the needles, a common support for the weft guides, and means for causing vertical movement of the support so coordinated with the support and with the selecting and actuating means that the rows of weft guides are moved past the needles in positions above the same, whereby the said movement past the needles can occur at least in part during retraction of the needles.

47. A knitting machine comprising a needle bed having needles, means for projecting and retracting the needles, means for feeding weft yarns to the needles comprising weft guides for the individual needles selectively movable into a first row and a second row, said weft guides and the needle bed being reciprocable relative to each other along the needle bed with each of the weft

guides in the first row being movable past a single needle and each of the weft guides in the second row being movable past a plurality of needles, means for causing said selective movement during operation of the machine, actuator means for causing the reciprocatory movement of the first and second rows, said actuator means including different movable means for the different rows such that the weft guides in course of selective movement between said rows move into engagement with the said different means during the operation of the machine, and weft guides being vertically movable to positions above the needles, and drive means to cause said vertical movement of the weft guides so that the movement of said rows past the needles occurs above the needles, said needles having hooks, said actuator means being so coordinated with the needle retracting means as to cause weft guides that move past one needle to lay their yarns into the needle hooks, and said needle retracting means comprising means for causing a retarded retraction of the needles at a point in the travel thereof so that said actuator means causes the laying-in of said yarns into the needles during said retarded retraction.

48. A knitting machine comprising a needle bed having needles, means for projecting and retracting the needles, means for feeding weft yarns to the needles comprising weft guides for the individual needles selectively movable into a first row and a second row, said weft guides and the needle bed being reciprocable relative to each other along the needle bed with each of the weft guides in the first row being movable past a single needle and each of the weft guides in the second row being movable past a plurality of needles, means for causing said selective movement during operation of the machine, actuator means for causing the reciprocatory movement of the first and second rows, said actuator means including different movable means for the different rows such that the weft guides in course of selective movement between said rows move into engagement with the said different means during the operation of the machine, said weft guides being vertically movable to positions above the needles, and drive means to cause said vertical movement of the weft guides so that the movement of said rows past the needles occurs above the needles, the means for causing selective movement of the weft guides comprising a jacquard, including releasable locking means for locking the weft guides of at least one row so as to remain in said row during a plurality of courses of the machine, and means for causing release of the releasable locking means upon completion of said courses.

49. A knitting machine comprising a needle bed having needles, means for projecting and retracting the needles, means for feeding weft yarns to the needles comprising weft guides for the individual needles selectively movable into a first row and a second row, said weft guides and the needle bed being reciprocable relative to each other along the needle bed with each of the weft guides in the first row being movable past a single needle and each of the weft guides in the second row being movable past a plurality of needles, means for causing said selective movement during operation of the machine, actuator means for causing the reciprocatory movement of the first and second rows, said actuator means including different movable means for the different rows such that the weft guides in course of

selective movement between said rows move into engagement with the said different means during the operation of the machine, said weft guides being vertically movable to positions above the needles, and drive means to cause said vertical movement of the weft guides so that the movement of said rows past the needles occurs above the needles, means including a carriage traveling along the needle bed from end to end thereof for extending a ground weft over the needles, means to cause a single traverse of the carriage after a plurality of courses of the machine, said traverse occurring continuously during the next succeeding plurality of courses of the machine, and means for causing vertical movements of the carriage at the ends of the needle bed so that the carriage is raised above the needles when it begins its traverse and is lowered to lower the ground weft below the needles when the carriage completes its traverse.

50. A knitting machine comprising a needle bed having needles, means for projecting and retracting the needles, means for feeding weft yarns to the needles comprising weft guides for the individual needles selectively movable into a first row and a second row, said weft guides and the needle bed being reciprocable relative to each other along the needle bed and with each of the weft guides in the first row being movable past a single needle and each of the weft guides in the second row being movable past a plurality of needles, means for causing said selective movement during operation of the machine, actuator means for causing the reciprocatory movement of the first and second rows, said actuator means including different movable means for the different rows such that the weft guides in course of selective movement between said rows move into engagement with the said different means during the operation of the machine, said weft guides being vertically movable to positions above the needles, a common support for the weft guides and for the actuator means, and means to cause vertical movement of the common support with the movement of said rows of weft guides past the needles occurring above the needles.

51. A knitting machine comprising a needle bed having needles, means for projecting and retracting the needles, means for feeding weft yarns to the needles comprising weft guides for the individual needles selectively movable into a first row and a second row, said weft guides and the needle bed being reciprocable relative to each other along the needle bed with each of the weft guides in the first row being movable past a single needle and each of the weft guides in the second row being movable past a plurality of needles, means for causing said selective movement during operation of the machine, actuator means for causing the reciprocatory movement of the first and second rows, said actuator means including different movable means for the different rows such that the weft guides in course of selective movement between said rows move into engagement with the said different means during the operation of the machine, said weft guides being vertically movable to positions above the needles, and drive means to cause said vertical movement of the

weft guides so that the movement of said rows past the needles occurs above the needles, and the different movable means of the actuator means being caused to begin operation at different times, 5 first of the first row past its needles, and then of the second row past its needles, so that when the drive means causes downward movement of the weft guides, those of the first row have laid their yarn into the needles with those of the second row clearing their needles which are now substantially wholly retracted.

52. A jacquard knitting machine having knitting means, including a needle bed having needles, means to reciprocate the needles, means 15 including a carriage capable of traveling from end to end of the needle bed above the needles, means for vertically moving the carriage below and above the needles at each end of the needle bed, with the carriage being lowered while the needles are substantially retracted, said carriage serving to lay down a continuous weft to be engaged under the needles by the stitches.

53. A knitting machine having a needle bed having needles, yarn feeding carriers for the needles, said carriers being vertically movable to positions above the needles, means for causing said vertical movement of the carriers, said carriers being adapted to be disposed in a plurality of rows along the needle bed, the carriers of at 25 least one row being selectively movable into operating position in the other row, the carriers in one row being movable past a single needle and those in the other row being movable past a plurality of needles, means automatically selectively co-acting with said carriers and serving to actuate the same past a single or past a plurality of needles, and means for causing selective movement of the carriers between said rows before movement of the carriers to positions above the 30 needles.

54. A knitting machine including a needle bed having reciprocable needles, said needles having upwardly opening hooks, weft carriers for the individual needles selectively movable between different paths such that a weft carrier in one path is movable past a single needle and a weft carrier in the other path is movable past a plurality of needles, and means for actuating the weft carriers including means for causing selective movement of the weft carriers between said 45 different paths, the actuating means comprising portions for causing weft carriers that move past a single needle to lay their weft into the needle hooks and for causing weft carriers that move past a plurality of needles to lay their weft under the needles to avoid breakage of such weft by the needle hooks in the knitting of open and closed fabric sections, and means for projecting the needles outward of the needle bed and for re-tracting the needles, including means for causing retarded retraction of the needles at a point in the path of travel of the needles, while the weft yarn is being laid into the hooks thereof, said 50 weft carriers being vertically reciprocable, and means for causing vertical reciprocation of all of 55 the weft carriers simultaneously.
